APPARATUS FOR AUTOMATICALLY TESTING AND MAINTAINING THE CONCENTRATION OF SOLUTIONS FOR METAL TREATMENT

Robert M. Dick, St. Louis County, Mo., and George D. Howell, Alton, Ill., assignors to Peck's Products Company, St. Louis, Mo., a corporation of Missouri

Filed Mar. 6, 1967, Ser. No. 6,090

Term of patent 14 years

(Cl. D16—2)

FIG. 1

FIG. 2

FIG. 3

FIG. 4

FIGURE 1 is a top plan view of the apparatus for automatically testing and maintaining the concentration of solutions for metal treatment showing our new design.

FIGURE 2 is a front elevational view thereof.

FIGURE 3 is a side elevational view taken from the left hand side of FIGURE 2.

FIGURE 4 is a side elevational view taken from the right hand side of FIGURE 2.

The back of the apparatus is plain and unornamented. We claim:

The ornamental design for an apparatus for automatically testing and maintaining the concentration of solutions for metal treatment, as shown and described.
